UNITED STATES PATENT OFFICE.

HERMAN C. PRIEBE, OF BLUE ISLAND, ILLINOIS.

DRAFT GEAR.

Application filed July 17, 1923. Serial No. 652,132.

To all whom it may concern:

Be it known that I, HERMAN C. PRIEBE, citizen of the United States, residing at Blue Island, in the county of Cook and 5 State of Illinois, have invented a certain new and useful Improvement in Draft Gears, of which the following is a full, clear, concise, and exact description.

My invention relates to draft gears and 10 particularly to draft lugs employed in conjunction therewith.

In carrying out my invention the opposite draft lugs upon center or draft sills are merged or assembled into unitary structures 15 whereby each draft lug of such a structure supplements and strengthens the other and co-operates therewith in receiving draft strains and transmitting the same to the draft sills.

20 In the preferred embodiment of the invention each pair of opposite draft lugs has an upright transverse wing overlapping the upright transverse wing of the other and one of these transverse wings is formed with an offset to receive the other whereby both wings present a single abutting surface to the draft gear element whose motion is limited thereby. Strengthening ribs are also provided for the draft lugs, the strengthening 25 ribs of one draft lug being continued to underlie both wings so that not only is the wing of the draft lug carrying these particular ribs strengthened thereby but the wing of the complementary draft lug is also strengthened by these same ribs. The overlapping wings are desirably riveted and the latter ribs are continued into line with the rivets.

30 The invention will be more fully explained by reference to the accompanying drawings in which Fig. 1 is a longitudinal sectional view of a draft gear constructed in accordance with the preferred embodiment of the invention; Fig. 2 is a sectional view on line 2—2 of Fig. 1; Fig. 3 is a 35 perspective view of two complementary draft lugs in separated relation; Fig. 4 is a perspective view showing the draft lugs of Fig. 3 in assembly; and Fig. 5 is a sectional view on line 5—5 of Fig. 1.

Like parts are indicated by similar characters of reference throughout the different figures.

40 The center or other draft sills 1 and 2 are assembled in any suitable way with the body of the car. The draft gear of the in-

vention is interposed between these sills. This draft gear includes a coupler having a stem 3 and a yoke 4. The stem is formed with a transverse horizontal key slot there- 45 through at the inner end thereof while the outer end of the yoke is formed with similar slots 5 which are aligned with the slot in the stem. A key 6 is passed through all of these slots which, with the exception of the slot in the stem, are all longer than the width of the key so that the key may move longitudinally of the yoke in the operation of the gear. This key also passes through slots 7 formed in the center sills, these slots 50 being also longer than the width of the key to permit the key to move longitudinally of the sills.

Motion limiting draft lugs 8, 9 are riveted to the inner upright sides of the center sills 55 and are engaged by the inner end of the yoke. An outer follower 10 is surrounded or enclosed by the yoke and is engaged by the coupler butt to be moved inwardly thereby. Check plates 11 are at the forward end of 60 the gear and are engaged by the follower 10 to limit the extent of the outward movement of this follower.

The gear is further assembled with the draft sills by means of a key 12 passing 65 through slots 13 in the center sills and through a slot in the inner end of the coupler yoke. The slot in the coupler which receives the key 12 prevents material movement longitudinally of the gear between the 70 gear and yoke but the slots 13 are longer than the width of this key to permit the key to move longitudinally of the sills. The key 14 also takes part in assembling the gear with the sills, this key passing through a 75 slot in the outer follower 10 that snugly receives the same and passing through slots 15 in the center sills that are longer than the width of the key 14 to permit this key to move longitudinally of the sills. Springs 16 80 are upon the outer sides of the sills and between the outer ends of the keys 12 and 14, these springs pressing upon the follower 10 outwardly and away from the inner end of the coupler yoke. Two rockers 17, 18 are 85 also surrounded by the yoke. The outer rocker 17 has a curved outer face that is seated upon the curved inner end of the follower 10. The rocker 18 has a curved inner face that is seated upon the curved seat 110 19 formed integrally with the yoke. The rockers have opposed engaging or otherwise

co-acting faces whereby each has turning action upon the other. The rocker 18 engages a spring 20 seated within and carried by a transverse extension 21 of the yoke. This 5 spring serves to oppose the interaction of the rockers and thereby absorb the shocks to which the gear is subject.

The draft lug 8 has an inwardly projecting upright wing 8' and the draft lug 9 has 10 an inwardly projecting upright wing 9', this wing having its inner half portion offset the thickness of the wing 8' that projects into and substantially fills the recess formed by the offset. The overlapping ends of the 15 wing are secured together by rivets or bolts 22 whose outer heads are flush with the wing 8' and whose other heads may bulge. These rivets unite the wings into a unitary structure with the lugs, the lugs and their united 20 wings spanning the space between the draft sills. The surface presented by the wings 8', 9' of the inner end of the coupler yoke lie in one plane. The wing 9' reinforces the wing 8' directly. The wing 8' reinforces 25 the wing 9' through the intermediation of the rivets 22. The wing 8' is further reinforced by the ribs 8² and the wing 9' by the ribs 9². The latter ribs are desirably extended to underlie the overlapping portions 30 of both the wings 8 and 9, these ribs desirably terminating at the rivets or bolts 21 to strengthen the union of the wings in the region of these bolts or rivets.

While I have herein shown and particularly 35 described the preferred embodiment of my invention I do not wish to be limited to the precise details of construction shown as changes may readily be made without departing from the spirit of my invention, but 40 having thus described my invention I claim as new and desire to secure by Letters Patent the following:—

1. The combination with draft sills of a car; of oppositely arranged draft lugs each 45 having a wing projecting toward the other, the wings of the lugs overlapping; and bolts or rivets passing through the overlapping portions of the wings and uniting the same in a unitary structure.

50 2. The combination with draft sills of a car; of oppositely arranged draft lugs each having a wing projecting toward the other, the wings of the lugs overlapping and one being offset substantially the thickness of 55 the other which is received in the recess formed by the offset; and bolts or rivets passing through the overlapping portions of

the wings and uniting the same in a unitary structure.

3. The combination with draft sills of a 60 car; of oppositely arranged draft lugs each having a wing projecting toward the other, the wings of the lugs overlapping; ribs on the inner sides of the draft lugs and extending to the wings thereof; and bolts or rivets 65 passing through the overlapping portions of the wings and uniting the same in a unitary structure.

4. The combination with draft sills of a 70 car; of oppositely arranged draft lugs each having a wing projecting toward the other, the wings of the lugs overlapping and one being offset substantially the thickness of the other which is received in the recess 75 formed by the offset; ribs on the inner sides of the draft lugs and extending to the wings thereof; and bolts or rivets passing through the overlapping portions of the wings and uniting the same in a unitary structure.

5. The combination with draft sills of a 80 car; of oppositely arranged draft lugs each having a wing projecting toward the other, the wings of the lugs overlapping; ribs on the inner sides of the draft lugs and extending to the wings thereof, the ribs on the 85 draft lug whose wing underlies the wing of the other draft lug extending to this underlying wing where it underlies the other wing; and bolts or rivets passing through the overlapping portions of the wings and 90 uniting the same in a unitary structure.

6. The combination with draft sills of a 95 car; of oppositely arranged draft lugs each having a wing projecting toward the other, the wings of the lugs overlapping and one being offset substantially the thickness of the other which is received in the recess 100 formed by the offset; ribs on the inner sides of the draft lugs and extending to the wings thereof, the ribs on the draft lug whose wing underlies the wing of the other draft lug extending to this underlying wing where it underlies the other wing; and bolts or rivets 105 passing through the overlapping portions of the wings and uniting the same in a unitary structure.

7. The combination with draft sills of a 110 car; of oppositely arranged draft lugs each having a wing projecting toward the other; and bolts or rivets uniting the wings in a unitary structure.

In witness whereof, I hereunto subscribe my name this 21st day of June A. D., 1923.

HERMAN C. PRIEBE.
